CLAIM

The ornamental design for a video camera, as shown and described.

DESCRIPTION

FIG. 1 is a top, front and left side perspective view of a video camera embodying the new design;

FIG. 2 is a bottom, rear and right side perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a left side elevation view thereof; and,

FIG. 8 is a right side elevation view thereof.

The broken lines depict portions of a video camera in which the design is embodied and form no part of the claimed design. Additionally, the dash-dot-dash lines denote the boundary of the claim and form no part of the claimed design.

1 Claim, 4 Drawing Sheets(56)
